UNDERWATER GOOGLES

Charles Henry Wilen and Alexandre Kramarenko,
Nice, FranceApplication September 9, 1938, Serial No. 229,068
In France September 23, 1937

6 Claims. (Cl. 2-14)

This invention relates to an apparatus in the form of goggles for permitting vision beneath the surface of the water on the part of the user or wearer of the goggles.

5 In an application filed September 4, 1937, by Alexandre Kramarenko, Serial No. 162,399, there is shown and described a submarine fishing gun which is adapted to shoot a pointed member, such as an arrow, by a person swimming, diving 10 or submerged under water. In order to do this effectively, the person should wear an apparatus such as the goggles to be described herein, in order to keep the water out of the eyes and thereby not obstruct the vision.

15 It is therefore the principal object of our invention to provide an apparatus or goggles which will snugly fit over the eyes of the user and effectively keep water out of the chamber formed in the apparatus forward of the part which engages the user's face.

20 While certain types of goggles have heretofore been proposed for underwater use, there are many objections to them; for example, certain designs use individual metal frames each with 25 a glass therein, like ordinary spectacles, the frames being made of aluminum which is subject to corrosion in salt water. We have found from practical tests in shooting fish under water in the manner described in the said Kramarenko 30 application that the glasses or goggles must lie flat across the face of the user; that is to say, the glass or glasses must be in the same plane, otherwise the person is quite likely to see double in the water due to the refraction of the light 35 rays passing through the water.

Our experience with prior types of glasses has been that the range of vision is limited therein, so it is a further object of our invention to provide goggles having a wide range of vision without any blur or double vision therefrom. To accomplish this, we have found, from experiments, that the goggle herein described fulfills the primary objects above stated, together with other objects which will be clear to one familiar with 45 the use of this type of apparatus.

Our invention will be readily understood and appreciated by reference to the annexed drawings, wherein:

Figure 1 is a view of a swimmer or user of one 50 form of our invention, in which an auxiliary air chamber is shown protruding upwardly from the goggles.

Figure 2 is a front view of the goggles shown in Figure 1, on a somewhat enlarged scale but 55 without the auxiliary air chamber.

Figure 3 is a rear view of Figure 2.

Figure 4 is a view looking down on the top of Figure 3.

Figure 5 is an end view of the goggles, a portion being broken away to show the means of attaching the holding means or strap.

Figure 6 is a section on the line 6-6 of Figure 4.

Figure 7 is a view on a much reduced scale showing a modified form of the apparatus.

In the various views, wherein like numbers refer to corresponding parts, 1 illustrates the bridge portion of the goggles having a formation 2 adapted to fit over the nose of the user. Fastened in the bridge portion 1 is a single piece or sheet of suitable glass 3, such as a non-breakable or non-shatterable type. The glass 3 is hermetically sealed into the bridge portion 1 which can be made of any suitable material, rubber vulcanized to the proper point being preferred. As shown in Figure 6 the glass 3 is set into a recess 4 in the bridge and a suitable cement 5 is used to hermetically seal the glass 3 in the forward portion of the bridge. As shown in Figure 2, the opposite ends or extremities of the bridge have a considerable taper 6 extending rearwardly to an opening indicated by the line 7 which is the boundary of what we term the rim portion of the apparatus.

As shown in Figures 1 to 6 inclusive, the rim is composed of two spaced flaps 8 and 9 which project outwardly from the bridge 1. Integrally connected between the flaps 8 and 9 are a plurality of spaced braces 10 which are of bendable material, it being understood that in our preferred form the entire structure is made of rubber so that the flaps 8 and 9 and braces 10 are bendable, and the outer flap 9 which engages the face of the user is adapted to be pressed toward the flap 8 through the bending of the braces 10.

At opposite ends of the rim formed by the flaps 8 and 9 there are reinforcements 11 and 12 which are preferably moulded integrally with the flaps 8 and 9; and passing below these reinforcements or anchor portions, are fasteners 13 and 14 which are in the shape of metal clamps. In order to prevent the metal fasteners 13 and 14 from cutting into the portions 11 and 12, we prefer to position over the fasteners, behind the portions 11 and 12, reinforcement members 15 and 16 which are preferably in the form of rubber tubing which is slipped over the fasteners before they are forced into closed position when assembled to the goggles. Joining the fasteners 13 and 14 is a flexible strap 17 which can be adjusted to get the right tension through the

medium of the member 18 forming a part of the fasteners 13 and 14.

By forming the rim in this manner, we get a self-adjusting and easy engagement surface of 5 substantial width or area around the eyes of the user, so that when the strap 17 is properly adjusted, a water-tight contact is insured at the face-engaging portion of the apparatus.

It will be noted that the glass 3 is spaced a 10 material distance forwardly of the rim and that due to the angular spread 7, shown more particularly in Figure 2, and further due to the fact that a single continuous piece of glass is used, a wide and unobstructed range of vision is 15 obtained. Furthermore, the structure being made of rubber is substantially unbreakable, non-corrosive and impervious to water.

In certain cases the bridge 1 may be provided with an orifice 19 in which may be inserted the 20 stem 20 of an auxiliary air container or chamber 21 which may be used when the swimmer is going into relatively deep water, for example, to a depth of twenty feet or thereabout, in which case the pressure of the water acting on the container— 25 which is made of compressible material such as soft rubber—will compress the same and force the air therein into the chamber formed between the glass 3 and the facial rim, thereby tending to balance the pressure of the water against the 30 glass 3 and relieving the pressure against the face of the swimmer. When the air container 21 is not used, the hole 19 is stopped up with a suitable plug 22.

In Figure 7 the rim 23 is formed so as to provide a sealed space within which air may be forced through a suitable air valve 24 provided in the rim which may be made integral with the portion 1, or made separately and attached thereto in any satisfactory manner, so as to form a 40 unitary structure which will act the same as the form shown in Figures 1 to 6 inclusive. Likewise, in this form the rim may be provided with an opening 19 to take the auxiliary air chamber or container 21.

45 From the above description it will be seen that the glass 3 is always in the same plane and the arrangement is such as to provide the clearest vision possible, thereby lessening the fatigue and discomfort of the user. It will be noted in passing that the strap 17 is preferably made wide enough so as to cover the opening into the ears of the user, further adding to the comfort of the user; in fact, the strap may carry suitable pads to entirely cover the ears and keep water out of 55 them.

It is also to be further noted that the construction of the goggles is such as to leave the nose and mouth free for normal breathing, which we believe to be a new and important feature in a 60 mono-goggle using a single glass in the same plane.

Having thus described the preferred form of our invention, what we claim is:

1. Goggles especially for use under water comprising a bridge portion impervious to water and adapted to fit on the nose and across the eyes of a user, a single piece of plate glass hermetically sealed in and carried by the bridge portion and forming the forward wall of a chamber, said 65 chamber having a rim at a substantial distance 70

to the rear of the glass and adapted to fit the face of the user, said rim being impervious to water but readily compressible and having a contact area so as to insure that the chamber is securely closed when in place on the user, and 5 means for holding the goggles securely in place on the head of the user.

2. Goggles especially for use under water comprising a bridge portion impervious to water and adapted to fit on the nose and across the eyes of a 10 user, a single piece of plate glass carried by the bridge portion a substantial distance forwardly of the eyes and sealed in position on the bridge, the goggles having a rim impervious to water spaced from the glass and formed to fit around 15 the eyes of a user and being compressible so as to yield to a holding force, the rim opening having a length to span across the eyes of a user while the opening in the bridge which is closed by the glass is materially greater than said rim 20 opening, and means for holding the goggles onto the head of a user so the rim will make a substantially water-tight joint with the user's face.

3. Underwater goggles as set forth in claim 2, further defined in that the rim comprises two 25 spaced flaps extending outwardly from the bridge portion and having bendable braces spaced at intervals between the flaps, the outer flap being the one which directly engages the face of the 30 user.

4. Apparatus for seeing under water comprising a structure to be worn over the eyes of a user, said structure including a bridge of material impervious to water and having a formation to fit the nose, a single glass plate carried by the 35 front portion of the bridge and sealed therein, the structure having a rim spaced from the glass and adapted to make a single-loop contact around the eyes of a user, the glass being materially longer lengthwise of the bridge than the longitudinal length of the opening formed by the rim to provide wide-angle vision through the glass, the rim being compressible, and means for holding the structure onto the head of a user so as to compress the rim and form a closed chamber 45 around the eyes.

5. Apparatus as set forth in claim 4, further characterized in that a compressible air container is carried directly by the bridge, said air container having a passageway into the space between the glass plate and the face of a user whereby when the user goes into relatively deep water the air in said container is forced by the pressure of the water on the container into said space as and for the purpose described. 55

6. An apparatus as set forth in claim 4, further characterized in that a compressible air container is carried directly by the bridge, said air container having a passageway into the space between the glass plate and the face of a user 60 whereby when the user goes into relatively deep water the air in said container is forced by the pressure of the water on the container into said space as and for the purpose described, and still further defined in that the rim is in the form of 65 a sealed duct provided with means for passing air under pressure thereinto.
